CABLE-CARRIER SYSTEM.

1,157,190.

Specification of Letters Patent. Patented Oct. 19, 1915.

Application filed July 17, 1913. Serial No. 779,449.

To all whom it may concern:

Be it known that I, FRED R. TAISEY, a citizen of the United States, residing at Lowell, in the county of Middlesex and 5 State of Massachusetts, have invented certain new and useful Improvements in Cable-Carrier Systems, of which the following is a specification.

This invention relates to apparatus, disposed at stations of a cable carrier system, for despatching and receiving carriers, and is particularly adapted to what are known as high-line drop stations in systems of this character. Features thereof may also be employed to advantage in low-line systems, and indeed in systems other than those using a cable for the transmission of carriers.

One of the objects of the present invention is to provide an improved means for elevating a carrier from a station or point disposed at a relatively low level, to a track at a higher level and then to automatically connect the carrier to a propelling cable or otherwise subject it to a propulsive effort, in such manner as to avoid collisions with other carriers *en route* past the station.

Another object of my invention is to provide a carrier-hoisting mechanism which is set into operation by a downward push 30 upon the carrier itself, after the latter has been inserted in said mechanism. I have further aimed to provide an improved means whereby this hoisting mechanism may be intermittently operated, as needed, 35 by power derived from the cable or like means which propels the carriers along the main track.

Still another object of the invention is to provide an improved means for operatively 40 engaging and disengaging carriers with the propelling means.

These and other objects of my invention will be hereinafter referred to and the novel elements and combination of elements 45 whereby they may be attained will be particularly pointed out in the claims appended hereto.

In the drawings I have exemplified certain preferred forms of the apparatus in 50 question, but I am aware that various other changes and modifications than those shown may be made herein without departing from

the spirit of my invention and I hence desire to be limited only by the scope of said claims broadly considered in the light of the 55 specification.

Referring to the drawings: Figure 1 is a front elevation of a high-line drop station. Fig. 2 is a section of the apparatus shown in Fig. 1, taken on line II-II of said 60 figure; the station proper being shown in side elevation. Fig. 3 is a detail section taken on line III-III of Fig. 1. Fig. 4 is a fragmentary rear elevation of the mechanism for tripping free the carrier cable-gripping device and for thereafter causing said device to reengage the cable. Fig. 5 is a front elevation of a modified form of high-line drop station; the carriers on the main track having in this type of apparatus the 70 right of way over carriers being delivered to said main track from the station. Fig. 6 is a front elevation of still another form of the apparatus in question; the carriers from the station having the right of way over carriers traversing the main track in this form of device, as in the device shown in Fig. 1. Fig. 7 is a section taken on line VII-VII of Fig. 6, and Fig. 8 is a horizontal detail section taken on line VIII-VIII of Fig. 6. 80

The several modifications will be separately discussed.

Considering first the apparatus shown in Figs. 1, 2, 3 and 4: The main track in the present instance comprises an upper or incoming track 1 preferably adapted to support carriers horizontally; both portions of the track being disposed in a horizontal plane in a known manner. The lower, or outgoing track in the apparatus exemplified 90 has the rails 2-2 thereof disposed in the same vertical plane, but I do not wish to be limited in any way to such disposition of the rails where the claims do not clearly specify such arrangement. 95

The main tracks have been respectively designated forwarding and return tracks, with respect to the drop or clerk's station and not with respect to the cashier's station. A track comprising rails 3-3 extends 100 up vertically from a point convenient to the operative and is adapted to deliver carriers to the track the rails of which have been designated 2 (and which may hence for

brevity conveniently be referred to as track 2) when a switch 4 is in its elevated position, indicated by dot and dash lines at 4' in Fig. 1. A cable 5 serves to propel carriers in the direction indicated by the arrows adjacent thereto, along the respective main tracks; and this cable it will be noted is normally substantially free from kinks or bends where passing a station of the character in question; a feature of considerable importance. An independent drop track 6—6 is adapted to receive carriers from a switch 7 to which selective carriers are delivered in a known manner from the upper or horizontal track 1. The respective track sections and switch are suitably connected together and supported by brackets or connections 8, 9, 10, 11, 12, 13, 14, 15 and 16, the switch 4 being mounted upon a shaft 17 journaled in the bracket 9 and most of the remaining brackets serving further to support operating cams, or the like, in the manner herein-after described.

The shaft 17 has mounted thereon adjacent its rear extremity an arm 18 which has journaled in its free end a spindle 19 upon the rear extremity of which is keyed a spool 20 and upon the inner end of which is a small pulley 21. This pulley is preferably provided with a roughened surface at the periphery 22 thereof to better adapt it for driving engagement with the cable 5.

Journaled in the lower portion of the bracket 10 is an idler 23 upon which normally the cable 5 lightly rests, but which, when the arm 18 is rotated into its position indicated by dash and dot lines 18', kinks or bends the cable into driving engagement with the pulley 21. At such time obviously the spool 20 will be rotated in the direction of the arrow adjacent thereto and said spool will thereby wind up upon itself a hoisting cord 24. This cord has its lower extremity attached to a pusher 25, which, as indicated in Figs. 1 and 2, rides between the rails 3—3. This pusher may be made of fiber or other suitable material and carries a hook 26, the function of which will be hereinafter referred to. The respective rails 3 are bent out as at 27 to provide an opening through which the guide or retaining lugs 28' of the carrier 28 may be inserted into operative engagement with the pusher 25 as shown in Fig. 1.

The carrier 28 may be of any suitable description adapted to co-act with the rails, but it is preferably of substantially the form shown in Fig. 4; the bottom of the carrier carrying a cable-gripping lug 29 and being slotted as at 30, in a known manner, to permit the projection through said slot of a pivoted cable-gripping member 31.

To despatch the carrier it is pushed downwardly by the hand of the operative and thereby depresses the pusher 25 to its dotted

line position 25', shown in Fig. 1. This causes the hoisting cord 24 to swing the arm 18 downwardly until the pulley 21 is in driving engagement with the cable 5. The bridge 4 is raised at the same time to its dotted line position 4' and these parts are held in such position by a latch 32, pivoted at 33 to an extension of the bracket 9; the operating position of latch 32 being indicated by dotted lines 32' and the latch at such time being in engagement with a shoulder 34 on the bridge 4. The spool 20 winds up cord 24 in manner aforesaid and the carrier is driven upwardly by the pusher around the bend in track 3 into engagement with track 2. If by chance the pivoted grip member 31 of the carrier is in its closed position, a cam 35 in the path of the ascending carrier will force this member into its open position preparatory for its engagement with the cable 5.

The bridge 4 is slotted at its free end, as at 36 (see Figs. 1 and 3) for the reception alternately of the reduced sections 37—37' of the longer rail 3 and upper rail 2, so that whether the bridge is down or up, it is rigidly held against lateral movement. The rear side of said bridge, as viewed in Fig. 1, carries a knob or button 38 which extends out beyond the cable 5 so that as the bridge is elevated the cable first engages the rounded upper surface of this button and then slips downwardly thereover till it rides over the preferably bluntly pointed extremity 39 and around against the curved under surface 40 of said button, as indicated in Fig. 3. This feature is of great importance since this exceedingly simple device provides means for enabling the ascending carrier to dispose the cable 5 between the jaws of its grip by reason of the fact that the jaw 29 presses upwardly against the cable as the carrier emerges from track 3, which in turn presses the cable upwardly against the cam-acting surface 40, and the shape of the latter is such that the cable is displaced side-wise to clear lug 29; the cable, being under tension, thereafter emplacing itself under said lug, so that when the pivoted grip member 31 encounters the grip-closing cam 41, the carrier is at once operatively engaged with the cable.

A spring 42 gives the latch 32 a bias for its operative position, while a spring 43 tends to return the bridge and its associated movable parts to their normal positions, shown in full lines in Fig. 1.

When the carrier has been nearly entered upon track 2, the cam acting upper surface of the hook 26, at the side of the pusher 25, engages a projection 44 upon the latch and swings the latch to its open position releasing the bridge. The bridge cannot drop, however, more than just sufficient to prevent its becoming re-latched, since the carrier

will at such time support its free end and hence until the carrier has been fully entered, by its momentum, upon track 2, said bridge cannot close. The hook 26 also serves to limit the upward travel of the pusher and since at practically the instant after it encounters the latch, the bridge is allowed to close, the tension upon the hoisting cord is relieved and the weight of the pusher returns it to its normal or lower position; cord 24 unwinding from its spool and the parts described being then in position for the despatch of a second carrier.

The means for preventing collisions between carriers *en route* along main track 2 and carriers being despatched from the clerk's station will now be described.

Pivotedly connected at 45 to the arm 18 is a bent link 46, the right hand end of which, as viewed in Fig. 1, is connected at 47 to an L-shaped member 48. The latter is pivoted at 49 to the bracket 12 and the distance between the pivotal axes 47 and 49 is substantially equal to the distance between the pivotal axes 45 and 17; so that the straight half of link 46, adjacent member 48, is always held parallel to the cable or track 2. Intermediate members 48 and 18 is a second L-shaped part 50 which is pivotally connected to the link 46 at 51 and also pivoted at 52 to bracket 11. The distance between axes 51 and 52 is again made equal to that between axes 47 and 49, and obviously members 48 and 50 rotate together, clockwise or counter-clockwise as the case may be.

The free end 53 of the member 48 is bent over as shown to adapt it for engagement with the pivoted element 31 of the carrier grip, so that when a carrier traveling over track 2 approaches a station from which a carrier is being despatched and the bridge of which station has been raised, its pivoted jaw or grip 31 strikes said end 53 and such carrier is released from the cable to continue on by momentum alone until it strikes the free end 54 of the member 50 which at such time is disposed in its dotted line position. This element positively stops the carrier. It will be observed, too, that the element 54 is also adapted to open the grip of the carrier as well as to stop the latter should the members 48 and 50 chance to have been rotated clockwise to their operative positions after the carrier traversing track 2 has passed member 48 but before it has passed member 50. It may also happen that two carriers are *en route* over track 2 immediately behind each other in which case both will be disengaged from the cable and brought to rest immediately to the right of the stop 54. Assuming now that one or more carriers are so disposed, the moment that the carrier being despatched from the station has passed from beneath the bridge 4, the latter

closes and thereby the grip-opener 53 and combined grip-opener and stop 54 are lowered while simultaneously the bar or link 46 is raised. The straight portion of the bar, when the bridge is open, lies immediately below the grip elements of the arrested carrier on track 2, so that as it rises its upper edge 46', indicated by dotted lines in Fig. 4, engages the pivoted jaw 31, shown by dotted lines in its lower position in said figure, and presses it upwardly a sufficient distance to enable the jaw to be snapped closed by its spring in the interior of the carrier bottom: although the movement of the cable alone when the pivoted jaw is brought into contact therewith will normally pull this part around the remainder of its travel into apposition with co-acting jaw or grip element 29.

Since the straight portion of the link 46 is relatively quite extended it is adapted to effect the engagement of a plurality of carriers with the cable simultaneously, and hence the one or more arrested carriers immediately resume their travel over track 2 as soon as the carrier leaving track 3 has been entered upon track 2 and its grip thrown into engagement with the cable in manner aforesaid.

Carriers arriving at the clerk's station for which they are intended are automatically removed from the return or incoming track 1 by the engagement of their selective lateral guides (not shown, since these are in common use) with the switch 55, in a known manner; the usual spreading or aperture 56 in the track 1 being provided to enable the carrier guide lugs 28' to free themselves from said track.

The usual grip opening cam 55' is provided and the carriers are delivered to track 6 in a known manner, descending this track until they come to rest in the relatively small radius loop 57. The novelty in this preferred receiving track, *per se*, principally resides in the provision of oblique cuts 58 in the respective rails thereof, at substantially the entrance to the loop 57, which permits of the ready withdrawal of lugs 28' of a given carrier therethrough while leaving no opening, such as at 27, through which a carrier may become inadvertently disengaged from said rails. As the carrier is lifted backward from the loop up toward the cuts 58 its lugs 28' easily enter themselves in these cuts by reason of the natural slight cant given to the carrier by the hand of the operator, while if several carriers have accumulated in this receiving track, the one in the loop grasped by the hand is removed while the others thereabove are lifted slightly so that but one carrier need be removed at a time.

Referring now to the modification shown in Fig. 5. Herein the carrier traversing

track 2 has the right of way over carriers being despatched from the station shown. The parts not otherwise particularly noted are substantially the same as in the previously described form of device and hence need not again be referred to. The essential difference between the two constructions resides in the substitution of a lever 60 pivoted at 61 to bracket 10 and having a connection 62 with the latch 32, in place of the link 46 and its associated parts. The connection at 62 is preferably a slotted one, to permit of free movement between the connected elements, and it operates in the following manner: Assuming that a carrier 28 is just being despatched when a carrier on the main track 2 approaches the station, as indicated by the dotted-outlined carrier shown to the right on said track, in Fig. 5. The clockwise movement of the latch as bridge 4 is opened swings the inner end of lever 60 downward and its outer end upward as also indicated by dotted lines in said figure. This disposition of the treadle-like free end of lever 60, however, places it in the path of the approaching carrier and if it has not re-descended before this carrier encounters it, it will be positively depressed by the engagement of said approaching carrier therewith, which will rock the lever clockwise and the latch counter-clockwise, releasing the bridge, when spring 43 immediately closes the same, at the same time lifting pulley 21 out of engagement with cable 5, so that the pusher 25 descends prematurely and with it the carrier being despatched, unless the latter has already succeeded in so nearly entering track 2 that its momentum carries it out completely thereinto; in which case its grip will engage cable 5 and both carriers will travel on thereafter one closely behind the other.

The spring 43 may, if desired, be so tensioned that the momentum of the follower or pusher 25 plus that of the carrier being despatched will afford in their fall a sufficient pull downwardly upon the hoisting-cord, as they reach substantially their lowermost positions in track 3, to effect a re-engagement of the pulley 21 with cable 5 and a re-latching of the bridge in its up-position. In such case the action is as follows: The carrier being despatched has, let us say, reached bracket 13, when the carrier on track 2 trips the latch and the bridge closes, this latter carrier immediately passing thereover. By the time that the through or main line carrier has cleared the bridge, however, the pusher and the carrier supported thereby will have dropped until they have nearly reached the positions in which they are shown in Fig. 1. Thereafter they will continue to descend under momentum and by gravity until the bridge is again raised and latched and the pusher again

drawn up. This time, if there be no immediately succeeding carrier on track 2 (which seldom happens) the pusher 25 will be pulled up sufficiently to discharge its carrier load onto track 2 in the manner above described. 70

In Figs. 6, 7 and 8, I have shown still another modification. In this construction the carrier being despatched has the right of way, as in the exemplification first described. Instead, however, of wrapping up 75 the hoisting cord upon a drum, the upper end of this cord is attached to a spring 63 the inner end of which latter is secured to bracket 10. The cord 24 extends forwardly from spring 63 around an idler 64, mounted 80 upon a traveling block or carriage 65, which rides upon auxiliary tracks or guides 65'; as best shown in Figs. 7 and 8. The cord 24 thence passes around idlers 66 and 67 and down to the pusher 25 to which it may 85 be secured as at 68. The weight of the pusher is sufficient to return the carriage to the position in which it is shown in Fig. 6, when displaced therefrom by the cable 5, and after being released from said cable in 90 the manner hereinafter described; and a bumper 69, provided with a compression spring 70, cushions the return of this carriage to its normal position. The carriage 65 carries upon one side thereof a jaw 71 95 and has pivotally mounted in operative relationship to this jaw a grip element or jaw 72 against the flattened hub of which a spring 73 bears in such a manner as to hold the pivoted jaw in its open as well as in its 100 cable gripping position, when moved into either of these positions; this spring further having a tendency to snap the jaw closed when it has been swung inwardly part way by the cam 74; which occurs when the carriage is retracted against the action of buffer spring 70 by a downward thrust upon the pusher 25, by means of the carrier being despatched. It may be here noted that spring 70 is sufficiently strong to resist the pull exercised upon the cord 24 by the descending 105 unloaded pusher after the despatch of a carrier, so that the cam 74 cannot inadvertently reengage the carriage with the cable 5. The grip mechanism comprising jaws 71 and 110 72 is in fact practically a duplicate of that provided upon each of the carriers and is intended to operate in substantially the same manner; jaws 71 and 72 of the carriage corresponding to the carrier jaws 29 and 31 115 previously referred to. The guides 65', as shown in Fig. 8, are spaced for the greater part of their length a sufficient distance 120 from the cable 5 to prevent the jaws of the carriage 65 becoming inadvertently engaged with the cable and also to insure proper clearance for the carriers traversing track 2. These guides, however, are inwardly directed toward said cable at their inner ends, 125 as shown, so that when the carriage is re- 130

tracted against the action of spring 70, the jaws 71-72 are brought into position where they may grip the cable.

The operation of the modification shown in Fig. 6 will, in view of the foregoing, be at once apparent. The carrier 28 is inserted at 27 and pressed downwardly against the pusher 25 which draws carriage 65 rearwardly and also causes it to approach the cable until its jaws are operatively engaged with the latter by a cam 74 which rocks the pivoted jaw 72 up until it engages cable 5, whereupon both spring 73 and the cable act to swing it into operative position; the cable drawing the carriage along with it and thereby pulling up the pusher and the carrier supported thereby until the carrier lifts the bridge 4 and is ejected onto the main track 2. The upward movement of the bridge by the carrier rocks the shaft 17 and thereby the arm 75 mounted in the latter, which operatively disposes the carrier-stopping members 48 and 50 through the intermediary of the link 46'; this link in the present instance being merely a straight bar. The bridge, further is locked in its upper position by latch 32, as in the preceding cases, and is unlocked by the engagement of the cam-hook 26 with the latch projection 44; the latch being normally pressed against the shouldered hub of the bridge by the spring 42. The hook 26, when sufficiently elevated, unlatches the bridge, and thereby lowers the trips 53 and 54 and reelevates the grip-engaging bar 46' shortly before the carriage 65 reaches the limit of its outward travel, so that the spring 63 is slightly stretched. The instant after the bridge is unlatched, however, a grip opening cam 75 in the path of jaw 72, swings the latter down, releasing the carriage from the cable and permitting it to be returned to its normal position; the cable having been pulled laterally out of its normal path by the carriage jaws and hence tending to immediately emerge from between these jaws when the latter are opened.

It will be noted that while one side of cam 74 serves to close the carriage jaw 72, as above described, the other side of this cam 50 serves to close upon the cable the corresponding jaw 13 of the carrier being despatched; so that this member performs a double function.

While I have exemplified a preferred form of reciprocable traction carriage provided with cable-gripping means together with devices for engaging and disengaging such means respectively with and from the cable, I am aware that other means for effecting reciprocation or to and fro movement of such a carriage may be used in lieu of the cable and a weight (pusher 25) or its equivalent, and hence do not desire to be limited to a cable propelled carriage of this description except when the claims specifi-

cally so indicate. I also desire to call particular attention to the provision of movable means, *e. g.* cams, trips or the like, such as the parts 53, 54 and 46' or 46, for arresting determined carriers under certain conditions 70 and for effecting their reengagement with, or re-subjection to the influence of, the cable or other propelling means.

The provision of means for receiving carriers from the return track which are substantially independent of the power-driven carrier delivering mechanism is of especial value in a system of the character described since it permits of the despatch of carriers from the station by said mechanism without interference therewith by carriers arriving at the station. Finally, it will be noted that the track or way leading from the station to the forwarding track is of substantially the same gage as said forwarding track, the carrier being successively directly in engagement with and propelled along both of said tracks.

I claim—

1. In a cable carrier apparatus, a track, 90 a cable for propelling carriers along said track, mechanism for delivering a carrier to said track at a determined point therein, and means, co-acting with said mechanism and movable in accordance with actuations 95 thereof into and out of the path of a part of a succeeding carrier traversing said track, for freeing from propulsive effort one of said carriers until the other has been moved into a determined position with respect to 100 said point.

2. In a despatch system, a way, means for propelling carriers along said way, mechanism for delivering a carrier to said way at a determined point therein, and means, co-acting with said mechanism and movable in accordance with actuations thereof into and out of the path of a part of a succeeding carrier traversing said way, for freeing from propulsive effort and checking forward 110 movement of one of said carriers until the other has been moved into a determined position with respect to said point.

3. In a cable carrier apparatus, a track, 115 a cable for propelling carriers along said track, power driven hoisting mechanism for elevating carriers from a point below said track substantially up to the level of the latter, means for operatively engaging said carriers with said cable, and a trip co-acting 120 with said mechanism and movable in accordance with actuations thereof into and out of the path of a succeeding carrier traversing said track, for freeing from propulsive effort one of said carriers until the other has been moved into a determined position with respect to the point in said track at which 125 said mechanism delivers carriers thereto.

4. A cable carrier system comprising two fixed main track sections, a fixed auxiliary 130

- track section and a movable track section along which carriers travel from one of said fixed main track sections to the other, a cable for propelling carriers along said fixed main track sections, and means, movable in accordance with said movable track section, for controlling the movements of a carrier traveling along one of said fixed track sections.
- 10 5. In a cable carrier apparatus, a track, a cable for propelling carriers along said track, mechanism for delivering a carrier to said track at a determined point therein, means for operatively engaging said carrier with said cable and means for preventing a collision involving said carrier and a second carrier traversing said track past said point, said last mentioned means including provisions for giving said first mentioned carrier the right of way over the second carrier and for releasing said second mentioned carrier from said cable.
- 15 6. In a cable carrier apparatus, a track, a cable for propelling carriers along said track, mechanism, operated by power derived from said cable, for delivering a carrier to said track at a determined point therein, means for operatively engaging said carrier with said cable and means for preventing a collision involving said carrier and a second carrier traversing said track past said point, said last mentioned means including provisions for giving said first mentioned carrier the right of way over the second carrier.
- 20 7. In a cable carrier apparatus, a track, a cable for propelling carriers along said track, mechanism for delivering a carrier to said track at a determined point therein, means for operatively engaging said carrier with said cable, means for preventing a collision involving said carrier and a second carrier traversing said track past said point, said last mentioned means including a trip adapted to be moved into the path of said second carrier before the latter reaches said point, said trip being controlled by said mechanism for movement into said path only when said mechanism is rendered operative to despatch a carrier.
- 25 8. In a cable carrier apparatus, forwarding and return tracks, a cable for propelling carriers along one at least of said tracks, a station having normally idle mechanism operated by power derived from said cable, for delivering a carrier to said forwarding track at a determined point in the latter, provisions for preventing a collision involving said carrier and a second carrier traversing said forwarding track past said point, said provisions including a movable carrier-controlling part adapted for engagement with said second carrier before the latter reaches said point, engagement of said part by said second carrier when said first men-

tioned carrier is being despatched operating to arrest the forwarding of one of said carriers, and means, substantially independent of said mechanism, for selectively receiving carriers from said return track which are destined for said station.

9. In a cable carrier apparatus, a track, a cable for propelling carriers along said track, mechanism for delivering a carrier to said track at a determined point therein, means for operatively engaging said carrier with said cable, and means for preventing a collision involving said carrier and a second carrier traversing said track past said point, said last mentioned means including a movable trip controlled by said mechanism and adapted to disengage said second carrier from said cable.

10. In a cable carrier apparatus, a track, a cable for propelling carriers along said track, mechanism for delivering a carrier to said track at a determined point therein, means for operatively engaging said carrier with said cable, and means for preventing a collision involving said carrier and a second carrier traversing said track past said point, said last mentioned means including a movable trip controlled by said mechanism and adapted to disengage said second carrier from said cable.

11. In a cable carrier apparatus, a track, a cable for propelling carriers along said track, mechanism for delivering a carrier to said track at a determined point therein, means for operatively engaging said carrier with said cable, and means for preventing a collision involving said carrier and a second carrier traversing said track past said point, said last mentioned means including a plurality of movable parts one of which is adapted to disengage said second carrier from said cable and a second of which is adapted to stop the so disengaged carrier.

12. In a cable carrier apparatus, a track, a cable for propelling carriers along said track, mechanism for delivering a carrier to said track at a determined point therein, means for operatively engaging said carrier with said cable, and means for preventing a collision involving said carrier and a second carrier traversing said track past said point, said last mentioned means including a movable stop controlled by said mechanism and adapted to arrest said second carrier.

13. In a cable carrier apparatus, a track, a cable for propelling carriers along said track, mechanism for delivering a carrier to said track at a determined point therein, means for operatively engaging said carrier with said cable, and means for preventing a collision involving said carrier and a second carrier traversing said track past said point, said last mentioned means including a device for arresting said second carrier.

and also a carrier succeeding said second carrier and to disengage both of said last mentioned carriers from said cable.

14. In cable carrier apparatus, a track, a cable for propelling carriers thereover, and means mounted for movement into and out of the path of a carrier traversing said track, for disengaging said carrier from said cable.

15. In cable carrier apparatus, a track, a cable for propelling carriers thereover, and means mounted for movement into and out of the path of carriers traversing said track for arresting a plurality of carriers, one traveling substantially immediately behind another, and for disengaging all of said arrested carriers from said cable.

16. In cable carrier apparatus, a track, a cable for propelling carriers thereover, means mounted for movement into and out of the path of carriers traversing said track for arresting a plurality of carriers, one traveling substantially immediately behind another, and for disengaging all of said arrested carriers from said cable, and means for thereafter reengaging said carriers with said cable.

17. In cable carrier apparatus, a track, a cable for propelling carriers thereover, carriers each having a cable engaging device, and means for substantially simultaneously operatively engaging the said devices of a plurality of carriers, disposed one behind the other, with said cable.

18. In cable carrier apparatus, a track, a cable for propelling carriers thereover, carriers each having a cable engaging device, and movable means for substantially simultaneously operatively engaging the said devices of a plurality of carriers, disposed one behind the other, with said cable.

19. In cable carrier apparatus, a track, a cable for propelling carriers thereover, carriers each having a cable engaging device, means for substantially simultaneously operatively engaging the said devices of a plurality of carriers, disposed one behind the other, with said cable, and mechanism for automatically actuating said means.

20. In cable carrier apparatus, a track, a cable for propelling carriers thereover, a carrier having a grip adapted for engagement with said cable, and extended means for operatively engaging said carrier with said cable at any point at which said carrier may be disposed along a determined extent of said track.

21. In a cable carrier apparatus, a track, a cable for propelling carriers thereover, a carrier having a grip adapted for engagement with said cable, and extended movable means for operatively engaging said carrier with said cable at any point at which said carrier may be disposed along a determined extent of said track.

22. In cable carrier apparatus, a track, a

cable for propelling carriers thereover, a carrier having a grip adapted for engagement with said cable, a movably mounted grip-opening cam and means for actuating said cam.

23. In cable carrier apparatus, a track, a cable for propelling carriers over said track, a carrier having a part for engaging said cable, means for stopping said carrier *en route* over said track and disengaging it from said cable in accordance with service conditions in said apparatus, and means for thereafter automatically reengaging said part with said cable when said conditions permit.

24. In cable carrier apparatus, a track, a cable, a carrier adapted for operative engagement with said cable, movably mounted means along said track for disengaging said carrier from and engaging it with said cable, and mechanism for actuating said means.

25. In cable carrier apparatus, a track, a cable, a carrier adapted for operative engagement with said cable, means for disengaging said cable from said carrier, means for engaging said cable and carrier, one at least of said means being movably mounted, and operating connections between said means.

26. In cable carrier apparatus, a track, a cable, a carrier adapted for operative engagement with said cable, means for disengaging said carrier from said cable, means for engaging said cable with said carrier, and provisions whereby one of said means only is operative at any given time.

27. In a cable carrier apparatus, a station, forwarding and return tracks extending past said station, means for propelling carriers along said forwarding track and for delivering carriers to said forwarding track from said station, mechanism for preventing a collision involving a carrier *en route* over said forwarding track past said station and a carrier being despatched from said station, said mechanism including provisions for temporarily arresting the forwarding movement of one of said carriers and thereafter causing said forwarding movement to be resumed, and means, substantially independent of the delivering means aforesaid, for receiving carriers from said return track.

28. In cable carrier apparatus, a station, a track extending past said station, means for propelling carriers along said track and for delivering carriers to said track from said station, and mechanism for preventing a collision involving a carrier *en route* over said track past said station and a carrier being despatched from said station, said mechanism including carrier grip-tripping and stopping means for arresting the forwarding movement of one of said last two mentioned carriers.

29. In cable carrier apparatus, a station, a

- track extending past said station, means for propelling carriers along said track and for delivering carriers to said track from said station, mechanism for preventing a collision involving a carrier *en route* over said track past said station and a carrier being despatched from said station, said mechanism including carrier grip-tripping and stopping means for arresting the forwarding movement of one of said carriers, and co-acting means for thereafter automatically re-subjecting the arrested carrier to the action of its propelling means.
30. In cable carrier apparatus, a station, tracks for forwarding carriers from and delivering carriers to said station, a cable for propelling carriers along the forwarding track at least, means driven by power obtained from said cable for delivering the carriers from said station to said forwarding track, mechanism for automatically disconnecting said means and cable after said carrier has been substantially delivered to said track by said power driven means, and means independent of said power driven means for receiving carriers from said return track.
31. In a cable carrier apparatus, the combination of a cable, with a carrier having a device adapted for engagement with said cable, a track along which said carrier is propelled by said cable, movably mounted means adapted to shift a portion of said cable laterally with respect to its normal line of travel into position where it may be operatively engaged by said device, mechanism for moving said last mentioned means, and means for driving said mechanism by power derived from said cable.
32. In a cable carrier apparatus, a track having therein an oscillatably mounted bridge across which carriers travel, a cable for propelling carriers along said track, a carrier provided with cable-engaging parts, and means carried by said bridge for operatively disposing a portion of said cable laterally with respect to its normal line of travel to adapt the cable to be effectively engaged by the cable-engaging parts of said carrier.
33. In a cable carrier apparatus, a track provided with a swingingly mounted carrier-guiding element, a cable for propelling carriers along said track, a carrier provided with cable-engaging parts, and means carried by said element for operatively disposing, by a swinging movement of said element, a portion of said cable to adapt the cable to be effectively engaged by the cable-engaging parts of said carrier.
34. In cable carrier apparatus, a track, a cable, a carrier adapted for operative engagement with said cable, movably mounted means along said track for disengaging said carrier from said cable and mechanism for actuating said means.

35. In cable carrier apparatus, a track, a cable for propelling carriers thereover, and cable-grip engaging means mounted for movement into and out of the path of a carrier traversing said track, for disengaging the grip of said carrier from said cable.

36. In cable carrier apparatus, a track, a cable for propelling carriers along said track, an auxiliary track for directing carriers into engagement with said first mentioned track, a flexible element for pulling carriers along said auxiliary track toward said main track, means for actuating said flexible element by power derived from the said cable, and means for freeing said flexible element from the action of said cable.

37. In cable carrier apparatus, a track, a cable for propelling carriers along said track, an auxiliary track for directing carriers into engagement with said first mentioned track, a flexible element for pulling carriers along said auxiliary track toward said main track, means for actuating said flexible element by power derived from said cable, and automatic means for freeing said flexible element from the action of said cable.

38. In cable carrier apparatus, a track, a cable for propelling carriers along said track, and means for delivering carriers to said track by power derived from said cable, said carrier delivering means comprising a reciprocable pusher and means for guiding said pusher.

39. In cable carrier apparatus, a main track, an auxiliary track leading into said main track, a carrier guide adapted to contact with at least one of said tracks to complete the same and movable in accordance with service requirements in said apparatus into one or the other of two positions, means for holding said guide temporarily in one of said positions, means for releasing said guide when a carrier arrives at a determined point in one of said tracks, means for checking the progress of a carrier traversing the other of said tracks, to prevent a collision involving one of said carriers, operative connections between said guide and said last mentioned means, and means, including a cable, for propelling carriers along said tracks.

40. In cable carrier apparatus, a main track, an auxiliary track adapted to deliver carriers thereto, a cable for propelling carriers along said main track, said carriers having means for engaging said cable, a pusher, driven by said cable, for propelling carriers along said auxiliary track, means in the path of carriers propelled by said pusher for operatively disposing the cable engaging means thereof to adapt the latter for engagement with said cable, and means for thereafter actuating said cable engaging means to grip said cable.

41. In cable carrier apparatus, a track, means for propelling carriers along said track, and mechanism for delivering carriers to said track, said mechanism including a hoisting cord and provision whereby a downward pull upon said cord starts the latter into operation. 70
42. In cable carrier apparatus, a main track, an auxiliary track adapted to deliver carriers thereto from a station, means for propelling carriers along said main track, and mechanism for propelling carriers along said auxiliary track, said mechanism including a support for a carrier to be despatched from said station and provisions whereby a downward push upon said support starts said mechanism into operation. 75
43. In cable carrier apparatus, a main track, an auxiliary track adapted to deliver carriers thereto from a station, means for propelling carriers along said main track, and mechanism, driven by power derived from said carrier propelling means, for propelling carriers along said auxiliary track, said mechanism including a support for a carrier to be despatched from said station and provisions whereby a downward push upon said support starts said mechanism into operation. 80
44. In cable carrier apparatus, a track, means for propelling carriers along said track, and mechanism for delivering carriers to said track, said mechanism including a hoisting cord normally extending down from said track, provisions whereby a downward pull upon said cord starts the mechanism into operation to raise said cord, and means for returning said cord to its normal position thereafter. 85
45. In cable carrier apparatus, a track, a drop-station, a cable for propelling carriers along said track, means for delivering carriers to said track from said drop-station by power derived from said cable and including a flexible element for hoisting carriers up from said station toward said track and guides along which said carriers are drawn by said element, and means for operatively engaging carriers delivered from said station with said cable, said track being substantially free from bends at said station and carriers traveling thereover past said station being thereby adapted to move in substantially a right line. 90
46. In cable carrier apparatus, a station, a track extending past said station, a cable for propelling carriers along said track, means for delivering carriers to said track from said station by power derived from said cable, said means including a power transmitting element operatively engageable and disengageable with said cable and said cable normally extending in a substantially right line past said element. 105
47. In a cable carrier apparatus, a station, a track extending past said station, a cable adjacent said track for propelling carriers thereover, and mechanism for delivering carriers to said track from said station by power derived from said cable, said track and said cable both being normally substantially straight at the point where said power is taken off from said cable. 110
48. In a cable carrier apparatus, a station, a track extending past said station, a cable adjacent said track for propelling carriers thereover, and mechanism for delivering carriers to said track from said station by power derived from said cable, said cable being normally substantially straight at the point where said power is taken off therefrom. 115
49. In carrier despatch apparatus, a main way, an auxiliary way leading thereinto, means for propelling a carrier along said auxiliary way, separate means for propelling said carrier along said main way, and mechanism for temporarily operatively connecting said two means whereby to drive one from the other for a limited period of time. 120
50. In cable carrier apparatus, a main way, a way disposed at an angle to said main way and leading thereinto, means for propelling a carrier along said second way, a cable for propelling said carrier along said main way, and mechanism for only temporarily operatively connecting said means and cable whereby to drive one from the other for a limited period of time. 125
51. In cable carrier apparatus, a main way, a way disposed at an angle to said main way and leading upwardly thereinto from a station, means, including a flexible element, for positively propelling a carrier along said second way, a cable for propelling said carrier along said main way, and mechanism for operatively connecting and thereafter automatically disconnecting said means and cable whereby to drive one from the other for a limited period of time. 130
52. In cable carrier apparatus, a main way, a way disposed at an angle to said main way and leading upwardly thereinto from a station, means, including a flexible element, for positively propelling a carrier along said second way, a cable for propelling said carrier along said main way, and mechanism for driving said means from said cable for a period of time merely sufficient to properly despatch said carrier from said station. 135
53. In cable carrier apparatus, a main track, a cable continuously driven for propelling carriers thereover, an auxiliary track of substantially the same gage leading into said main track, and discontinuously operated means, driven from said cable, when operative, for propelling carriers along said auxiliary track into said main track. 140
54. In cable carrier apparatus, a main

- track, a cable continuously driven for propelling carriers thereover, an auxiliary track of substantially the same gage leading into said main track, and discontinuously operated means, driven from said cable, when operative, for propelling carriers along said auxiliary track into said main track, said means including a pusher guidedly movable in said auxiliary track.
55. In cable carrier apparatus, a main track, a cable continuously driven for propelling carriers thereover, an auxiliary track of substantially the same gage leading into said main track, and discontinuously operated means driven from said cable, when operative, for propelling carriers along said auxiliary track into said main track, said means including a pusher, a hoisting cord attached to said pusher and a drum upon which said cord is wound.
56. In cable carrier apparatus, a track, a cable for propelling carriers along said track, a station, and means for delivering carriers from said station to said track, said means including an element adapted to have motion imparted thereto by said cable, means for engaging said cable and element to thereby actuate the latter and means for thereaft^e interrupting said engagement.
57. In cable carrier apparatus, a track, a carrier adapted to travel in said track, a cable for propelling said carrier along said track, a station, and means for delivering said carrier from said station to said track, said means including an element adapted to have motion imparted thereto by said cable, means for engaging said cable and element to thereby move the latter and means for interrupting said engagement after said carrier has been despatched from said station.
58. In cable carrier apparatus, a track, a cable for propelling carriers along said track, a station, and means for delivering carriers from said station to said track, said means including a revolute element adapted to be driven by said cable, means for engaging said cable and element to thereby drive the latter and means for thereafter interrupting said engagement.
59. In a cable carrier apparatus, a track, a cable for propelling carriers along said track, a station at a lower level than said track, and means including a hoisting element for elevating a carrier from said station to said track, and mechanism for only temporarily actuating said hoisting element by power derived from said cable, said mechanism comprising a power transmitting part movable directly into and out of engagement with said cable.
60. In a despatch system, a way, a carrier adapted to travel thereon, discontinuously operating, power-driven means for projecting said carrier into said way and including a flexible carrier-propelling cord and guides adjacent said cord for directing said carrier into engagement with said way, said cord moving in a path at variance with said way and said carrier adapted to traverse said way, after engagement therewith, substantially independently of said cord.
61. In a cable carrier apparatus, a main track, means, including an auxiliary track, for guiding carriers up from a drop-station into said main track, and power means, including a cable, for positively propelling carriers along said main and auxiliary tracks by power derived from said cable, said main track adapted to convey carriers past said station in substantially a right line and being substantially free from bends at said station.
62. In a cable carrier apparatus, a main track, means, including an auxiliary track, for guiding carriers up from a drop-station into said main track, said main track having a gap therein where said guiding means deliver carriers thereto and a movable part of said guiding means being adapted to bridge said gap, and power means, including a cable, for positively propelling carriers along both said main and auxiliary tracks by power derived from said cable.
63. In a cable carrier apparatus, a main track, an auxiliary track adapted to guide carriers, directly in engagement therewith, up from a station at a lower level than said main track into the latter, said main track having a gap therein through which carriers from said station are introduced and having movable means for substantially bridging said gap whereby carriers traversing said main track past said station may ride safely past said gap, and power means, including a cable, for positively propelling carriers along said main and auxiliary tracks by power derived from said cable.
64. In a cable carrier apparatus, a main track, an auxiliary track adapted to guide carriers up from a station at a lower level than said main track into the latter, said main track having a gap therein through which carriers from said station are introduced and having movable means for substantially bridging said gap whereby carriers traversing said main track past said station may ride safely past said gap, power means, including a cable, for positively propelling carriers along said main and auxiliary tracks and automatic means for preventing collision between a carrier *en route* along said main track and a second carrier *en route* along said auxiliary track.
65. A cable carrier system having a way-station, main tracks extending past said station, selective carriers to travel along said tracks, only some of which carriers pertain to said way-station, an auxiliary track extending upwardly from the station toward one of said main tracks, a drop-track lead-

ing down from another of said main tracks toward said station, a selective switch for switching off from said last mentioned main track only those carriers destined for the 5 particular way-station above referred to, while permitting other carriers to pass said station and travel on toward other stations, power means, including a cable, for propelling carriers along one at least of said main 10 tracks and also carriers despatched from said station along said auxiliary track by power derived from said cable, said auxiliary track adapted to be directly engaged by carriers traversing the same and to properly deliver said carriers to the corresponding 15 main track regardless of whether said carriers belong to said particular way-station or to another station along said main tracks, said auxiliary track being free from 20 any selective switch of the type aforesaid which would discriminate between selective carriers, whereby when a carrier corresponding to another way-station than that first mentioned is inadvertently despatched from 25 said first mentioned station, said carrier will freely traverse said auxiliary track and deliver to the corresponding main track.

66. In cable carrier apparatus, a main track, an auxiliary track adapted to deliver carriers thereto from a station, means for propelling carriers along said main track, and mechanism for propelling carriers along said auxiliary track, said mechanism including a support for a carrier to be despatched 30 from said station and provisions whereby the exertion of a determined displacing effort upon said support renders said mechanism operative.

67. In cable carrier apparatus, a main

track, an auxiliary track adapted to deliver 40 carriers thereto from a station, means for propelling carriers along said main track, and mechanism, driven by power derived from said carrier propelling means, for propelling carriers along said auxiliary track, 45 said mechanism including a support for a carrier to be despatched from said station and provisions whereby the exertion of a determined displacing effort upon said support renders said mechanism operative. 50

68. In cable carrier apparatus, a station, a track extending past said station, a cable for propelling carriers along said track, means for delivering carriers to said track from said station by power derived from 55 said cable, said means including a power transmitting element operatively engageable and disengageable with said cable, and means for engaging said element with said cable. 60

69. In a cable carrier apparatus, a station, a track extending past said station, a cable adjacent said track for propelling carriers thereover, and mechanism for delivering carriers to said track from said station by power derived from said cable, said track being substantially free from off-sets other than such as may be incident to the location of the station in a usual curvature in the track, said mechanism including rails, extending to said station, with which rails despatched carriers are directly in engagement. 65

In testimony whereof I have affixed my signature, in the presence of two witnesses.

FRED R. TAISEY.
